EUGENE L. KEYES, OF BOSTON, MASSACHUSETTS, ASSIGNOR TO UNITED SHOE MACHINERY COMPANY, OF PATERSON, NEW JERSEY, A CORPORATION OF NEW JERSEY.

HOLDDOWN FOR LASTING MACHINES.

1,120,822.

Specification of Letters Patent.

Patented Dec. 15, 1914.

Application filed September 3, 1910. Serial No. 380,400.

To all whom it may concern:

Be it known that I, EUGENE L. KEYES, a citizen of the United States, residing at Boston, in the county of Suffolk and State of Massachusetts, have invented certain Improvements in Holddowns for Lasting Machines, of which the following description, in connection with the accompanying drawings, is a specification, like reference characters on the drawings indicating like parts in the several figures.

This invention relates to hold down devices for use in connection with bed lasting machines of a well known commercial type, such for example as shown in U. S. Letters patent to Brock, No. 1,018,477, dated Feb. 27, 1912, to which reference may be had for the description of the machine in general.

An important feature of this invention is found in the foot. In its preferred form as shown the foot is of spring metal and is rotatably mounted on its carrier which in turn is movable to present the foot in any desired position lengthwise, laterally or angularly over the shoe. The foot is formed and mounted to engage by its toe or front end first and in practice this is placed upon the tip of the toe of the innersole just inside of and against the channel lip where it is held while the treadle is further depressed. The foot is bent or inclined downwardly toward the toe and as the downward pressure is applied the engaging portion is more or less forced forwardly to push against the inner-sole lip where it holds the innersole firmly against the backward pressure of the lasting plates or wipers. As the downward pressure is completed the heel of the hold down descends unyieldingly upon the shoe bottom and furnishes the firm abutment to withstand the upward wipe of the lasting plates tending to lift the last. It will thus be seen that this hold down comprises means to press downwardly and slightly forwardly at the toe, said means being adapted to engage against the innersole lip and furnish an abutment therefor and crowd the inner-sole forwardly enough to keep it straight and smooth, and means also to press hard down upon the ball of the last. The illustrated formation has the advantage of holding down upon the toe of the last to an adequate extent and in a satisfactory manner,

and of holding down the last as a whole by pressure applied over the ball and at a distance from the toe lasting apparatus which avoids any interference with the use of the wipers or of the hand pincers sometimes employed as auxiliary lasting devices. The downward inclination of the foot has the double advantage that it gives adequate pressure at the toe end, particularly when supplemented by the action of the heel of the foot upon the ball of the last without any upstanding braces which would be in the way of the toe lasting operation and that the bend or inclination of the yielding foot or resilient hold down member enables it to adapt itself automatically to any "spring" or longitudinal inclination of the bottoms of the lasts which are being used.

A further object of the invention is to provide adjustment of the hold down laterally of the shoe which may be readily effected and which will not be likely to be accidentally disturbed during the operation of the machine.

Further features of novelty relate to mechanism for holding the hold down depressed and for releasing it and to various relations and combinations of parts to be subsequently described.

In the drawings Figure 1 is a sectional view of a lasting machine with my improved device incorporated therein. Fig. 2 is a detail perspective showing the hold down head mounted in operative position upon a shoe and the toe lasting wipers in inoperative position. Fig. 3 is a sectional detail showing the means for frictionally holding the carrier of the hold down in its adjusted position laterally of the shoe.

In the drawings the reference numeral 2 indicates the frame of the machine. To the frame of the machine back of the lasting heads is secured at 4 a sleeve 6 which is held in position upon a rod 7 by collar 9. Passing through the sleeve 6 is a hold down post 8 having a slot 10 cut therein which is engaged by a pin 12 seated in the sleeve 6 to prevent rotation of the post 8 and permit longitudinal movement thereof. The hold down head comprises a collar 16 rigidly secured to the post 8 by a set screw 18, a rotatable head or block 20 loosely mounted upon the upper end of the post 8 and a col-

lar 22 rigidly secured to the post 8 and carrying a stop pin 24 with which a stop pin 26 seated in the block 20 engages when the hold down carrier 38 is swung into its inoperative position as shown in Fig. 1. The hold down carrier is automatically swung into this inoperative position, when released from the work, by a spring 30 which is attached at one end to a lug 28 carried by the block 20 and at the other to the collar 16 which is rigidly clamped to the post 8 by the set screw 18.

Upon the upper end of the block 20 is an enlargement having therein ways 36 through 15 which slides a hold down carrier 38. The construction of the ways 36 is such that the carrier 38 has a free sliding movement therein, and to provide sufficient friction to hold the carrier in adjusted position against ordinary stresses the device shown in Fig. 3 is provided. A hole is made through the enlarged portion of the block 20 extending through to the carrier 38 and in this hole is seated a cylindrical block 35 engaging a 25 slot 41 in the side of the carrier 38 and spring pressed thereagainst by a spring 37 which is backed up by a screw plug 39. The pressure of the block 35 upon the carrier creates sufficient friction to hold the carrier in its adjusted position.

The forward end of the carrier 38 is reduced at 40 and through the reduced portion extends a connector in the form of a bolt 42 having a head 44 provided with teeth for 35 engaging the innersole and with a thumb nut 46. The bolt head thus forms the heel of the hold down foot. Between the head 44 and the end 40 of the hold down carrier 38 is introduced a resilient hold down foot 40 member 48 which is provided with a slot for that purpose. A thumb nut 46 enables the hold down foot member 48 to be clamped to the hold down carrier in any position of angular adjustment. The forward end of 45 the hold down member 48 is bent downwardly and provided with a roughened toe 50 for engagement with the edge of the innersole. It will be seen that as the toe 50 engages the toe portion of the innersole behind the lip and is straightened by further downward movement of the hold down arm, the end thereof presses against the lip and tends to force the innersole forwardly to its 55 normal position flush with the edge of the last.

From the mechanism described, it will be seen that the hold down carrier 38 may be swung from its inoperative position, as shown in Fig. 1, to its operative position, 60 as shown in Fig. 2, that the carrier may be adjusted laterally or angularly relatively to the shoe and that the hold down member 48 may be adjusted relatively to the carrier 38.

65 It remains to provide mechanism for

forcibly depressing the hold down member upon the shoe. To accomplish this the operator depresses a treadle 60 fulcrumed at 64 and connected at 70 with a connecting rod 66 which is pivoted at the other end to 70 the post 8. The connecting rod which connects the pedal lever 60 with the post 8 is composed of a part 72 pivoted to the post 8, a part 68 pivoted to the pedal lever 60 and an intermediate portion 66 having right 75 and left hand threads upon its opposite ends threaded into the holes into the parts 72 and 68. The length of the connecting rod may thus be adjusted by turning the part 66 relatively to the parts 72 and 68 80 and the parts may be locked in adjusted position by a set nut 69.

For locking the pedal in depressed position a ratchet bar 78 having upwardly directed teeth is provided which slides in 85 ways in a block 79 attached to the frame of the machine. The ratchet bar is provided with a shoulder 81 engaging the pedal lever for sliding engagement and a pin 80 is passed through the ratchet bar below the 90 lever. Upon the upper portion of the block 79 are provided lugs carrying a pivot 86 of a pawl 84 having downwardly directed teeth which is normally held in engagement with the ratchet bar by a spring 88. A connecting rod 90 pivoted to a projection on the pawl 84 extends to and is adjustably connected with a knee lever 96 having a knee 95 engaging portion 100 and pivoted at 98 to the machine frame. A lug 94 is pivoted to 100 the knee lever 96 and on the rod which passes through the lug 94 are provided set nuts 92 in order that the length of the rod may be adjusted. When the pedal lever is depressed, it will be seen that the ratchet 105 bar 78 is carried with it and slides beneath the pawl 84 which prevents return movement. When, however, it is desired to release the down hold, the knee lever 100 is pressed which, rocking upon its pivot 98, 110 pulls upon the rod 90 and unseats the pawl 84 from the ratchet bar 82 thus releasing the pedal lever which is retracted to normal position by the spring 76.

In the operation of the device, the operator after having placed a shoe in position to be fastened upon the machine swings the hold down carrier 38 over the innersole of the shoe and having adjusted the carrier laterally, longitudinally and angularly of 120 the shoe to the desired position, depresses the pedal lever 60 to move the hold down toward the bottom face of the shoe. The lowermost or downwardly bent end or toe of the hold down member 48 first comes in 125 contact with the innersole near the toe portion and as the downward movement of the hold down is continued, the hold down member 48 is straightened forcing the toe 50 and the innersole slightly toward the point 130

- of the toe till the rigid hold down 44 is brought in contact with the lower portion of the innersole. By depressing the pedal lever still further a firm unyielding pressure may be brought to bear upon the hold down for holding the innersole securely to the last during the upward wipe of the lasting plates which tend to lift the last. This operation of drawing up and wiping in the toe portion of the upper is performed with the aid of the toe lasting wiper plates 102, as shown in Fig. 2. During the toe lasting operation while the upper is being drawn up along the edge of the last it is apt to catch upon the edge of the innersole and raise it from the last. By providing the yielding hold down member or toe having engagement with the innersole near the point of the toe where it is most likely to be caught by the upper and a firm, unyielding pressure at the ball of the shoe, displacement of the innersole during the toe lasting operation is effectively prevented. When the lasting operation is sufficiently progressed so that the parts are no longer likely to be displaced, the operator, in order that he may work more conveniently upon the shoe, may release the hold down by pressing the knee lever 100 thus releasing the pedal lever, as described, and allowing the retractile spring 76 to raise the post 8 and consequently the hold down head and hold down. As soon as the hold down arm is clear of the shoe, the spring 30 operates to rotate the block 20 on the post 8 until the stop pin 26 engages the stop pin 24 where the hold down remains in inoperative position until required for use upon the next shoe to be lasted.
- Having described fully the invention in its preferred embodiment and having indicated in connection with the description the manner in which it is contemplated the machine may be used, I claim as new and desire to secure by Letters Patent of the United States:—
1. A lasting machine hold-down comprising a carrier movable into and out of an operative position where it extends transversely across a shoe supported in the lasting machine, a resilient foot member which is formed at its front to engage the toe of a welt shoe innersole against the inner side of the lip, and a connector attaching the rear end of said foot member to the carrier and extending below said foot member to present a shoe engaging face rigid with said carrier.
  2. A lasting machine hold-down comprising a carrier movable into and out of an operative position where it extends transversely across a shoe supported in the lasting machine, a resilient foot member which is formed at its front to engage the toe of a welt shoe innersole against the inner side
  3. A lasting machine hold-down comprising a carrier movable into and out of an operative position where it extends transversely across a shoe supported in the lasting machine, a resilient foot member which is formed at its front to engage the toe of a welt shoe innersole against the inner side of the lip and is inclined upwardly from said front end and terminates in a rear portion which is substantially parallel with the plane of the innersole, and a connector having a head arranged below the foot and clamping it to the carrier, the lower face of the head being above the normal plane of the front end of the foot member to engage the shoe only after said front end has engaged the toe and said member has sprung to allow said head to reach the plane of the innersole.
  4. A lasting machine hold-down comprising a rigid carrier movable into and out of an operative position where it extends transversely across a shoe supported in the lasting machine, a resilient foot member which is formed at its front to engage the toe of a welt shoe innersole against the inner side of the lip and extends obliquely upward and backward to the carrier in a relation requiring it to be bent or sprung in order to allow the carrier to come into holding down relation to the shoe, and a connector securing the rear end of the foot member to the carrier with said rear end out of position to contact with the shoe.
  5. A lasting machine hold-down comprising a carrier arm arranged to extend over the shoe supported in said machine and provided with a member to engage the innersole over the ball of the last, and a resilient finger directly connected to said arm and extending obliquely downwardly and forwardly therefrom to a plane below said ball engaging member and into position to apply downward and forward pressure yieldingly to the toe end of the innersole while the ball engaging member is approaching the innersole, said finger being formed and arranged to be bent upwardly and forwardly at its front end by such engagement with the innersole before the ball engaging member can contact with the work.
  6. In a lasting machine a hold-down comprising a hold-down head mounted for

- 5 tation about a vertical axis, and a carrier extending horizontally from said head and provided with an innersole engaging member and a resilient hold-down member directly connected to the carrier and extending forwardly and downwardly therefrom to a plane below said member into position to press downwardly and forwardly against the toe of the innersole prior to the engagement of said innersole engaging member with the work and to be bent upwardly and forwardly during the last portion of the movement of the innersole engaging member.
- 10 7. In a lasting machine having means for supporting a shoe in predetermined position, a hold-down post 8 guided for vertical movement at the rear side of the machine, a block 20 mounted on the post and limited to turning movement about the vertical axis of said post and having a long horizontal guideway forming a rigid bearing, a carrier 38 endwise adjustable transversely of the shoe in said bearing and restrained from turning movement therein, and a horizontally extending hold-down foot pivotally secured near one end to said carrier and formed to engage the shoe bottom over the ball of the last and also at a separate point over the toe.
- 15 8. In a lasting machine having means for supporting a shoe in predetermined position, a hold-down post guided for vertical movement at the rear side of the machine opposite the shoe, a guide block on said post, a carrier guided in said block, and a hold-down foot fastened at one end to said carrier and projecting forwardly therefrom to overlie the forepart of the shoe bottom and engage the ball and toe thereof, said carrier being adjustable endwise in said block to position its foot carrying end transversely of the shoe to permit the foot to be alined in uniform relation to the foreparts of right and left crooked lasts.
- 20 9. A hold down for lasting machines comprising a resilient member having one end adapted to engage the innersole of a shoe and the other provided with a slot, and a hold down carrier mounted for adjustment laterally of the shoe sole and provided with a bolt passing through the end thereof, the head of said bolt being adapted to engage the innersole of the shoe and to clamp the slotted portion of the resilient member against the under side of the hold down carrier.
- 25 10. A lasting machine hold-down mechanism having, in combination, suitable operating means and means moved thereby into operative engagement with a shoe after the shoe is in position for lasting and acting to press downwardly upon the innersole and in doing so to automatically move slightly forwardly at the toe to furnish an abutment for

the innersole lip and to crowd the innersole forwardly enough to keep it straight and smooth, and means for pressing hard down upon the ball of the shoe subsequently to the action of said innersole lip abutting means. 70

11. A hold-down foot comprising a resilient downwardly inclined, forwardly extending member 48, having a roughened toe 50, a roughened heel 44 normally located in a plane at a substantially greater distance 75 from the underlying face of the shoe bottom than is the toe 50, and a carrier 38 for said member and supporting connections through which movement of the hold-down vertically and horizontally into engagement with the shoe is effected after the shoe has been positioned for lasting and by which the toe is forced yieldingly and only thereafter the heel unyieldingly into engagement with the shoe. 80

12. In a hold down for lasting machines a hold down arm mounted for sliding adjustment substantially at right angles to the longitudinal axis of the shoe, means on the end of said arm for engaging the innersole 90 of the shoe, a resilient hold down member, means for securing one end of said member to the end of said hold down arm, and frictional means for holding said hold down arm in any position of lateral adjustment. 95

13. In a lasting machine, means for supporting a shoe, and a hold-down device mounted for movement in a direction perpendicular to the plane of the shoe bottom into engagement with a shoe supported in 100 position to be lasted and constructed and arranged to have automatically imparted thereto by continued pressure in the direction of such movement a forward thrust while in engagement with the shoe bottom. 105

14. A hold down for lasting machines movable into and out of engagement with the shoe during the lasting operation and comprising a toe portion engaging member and a ball portion engaging member, 110 said toe portion engaging member being normally depressed below the ball portion engaging member and resiliently supported substantially perpendicular to the plane of the innersole into engagement with the 115 work for imparting to said engaging members right line movement whereby the toe portion engaging member engages the innersole prior to the ball portion engaging member and is adapted to yield to permit 120 engagement of the innersole by the ball portion engaging member.

15. In a lasting machine a hold down comprising a rod mounted for vertical reciprocation, a member mounted for rotation about the axis of said rod and provided with ways, a hold down arm mounted for sliding movement in said ways and provided at one end with means adapted to engage the innersole of a shoe, and means 130

frictionally engaging said arm whereby it is held in adjusted position within said ways.

16. In a lasting machine a hold down comprising a vertically movable member, a member mounted for rotation about a vertical axis upon said vertically movable member, an arm mounted for horizontal adjustment upon said rotatable member, and means in said rotatable member for frictionally holding said arm in adjusted position.

17. A hold-down for lasting machines, innersole engaging members arranged one below the other, an arm supporting the same, means supporting said arm for longitudinal movement to permit lateral adjustment of the engaging member over the shoe and to prevent rotary movement of the arm, said supporting means being mounted for limited rotation in a horizontal plane, and resilient means normally holding said arm at one limit of its rotative movement.

18. A hold down for lasting machines comprising innersole engaging members, a vertically movable member connected therewith for depressing the same, a pedal lever connected with said vertically movable member, a ratchet bar connected with said lever, a bell crank lever having one member provided with teeth for engaging said ratchet bar, a knee lever, and a rod connecting the other member of said bell-crank lever to the knee lever whereby movement of the knee lever will effect disengagement of the teeth from the ratchet bar.

19. In a lasting machine, the combination of means to support a shoe, a hold-down, a hold-down head mounted at the back of the machine at one lateral side of the shoe, pedal means extending to the front side of

the machine for depressing said head, a slide having upwardly projecting teeth guided in the frame of the machine and connected with said pedal means, pawl means having 45 downwardly projecting teeth for normally engaging said upwardly projecting teeth, and means extending upwardly from the pawl and terminating in a knee pad on the front side of the machine arranged for operation by the knee of an operator standing in working position at the front of the machine for tripping said pawl means.

20. In a lasting machine, means for supporting a shoe, a hold-down device mounted for movement in a direction perpendicular to the plane of the shoe bottom into engagement with a shoe supported in position to be lasted and constructed and arranged to have automatically imparted thereto by 60 continued pressure in the direction of such movement a forward thrust while in engagement with the shoe bottom, and supplemental means 44 becoming operative after such forward thrust to clamp the shoe 65 against rearward displacement.

21. In a lasting machine, means for supporting a shoe, a hold-down, and means for actuating the hold-down toward the shoe supporting means to cause the shoe to be 70 clamped against the supporting means, said parts being constructed and arranged to cause the hold-down to exert automatically a forward pressure against the innersole during its shoe clamping movement. 75

In testimony whereof I have signed my name to this specification in the presence of two subscribing witnesses:
